CLAIM

The ornamental design for a mirror defogger, as shown and described.

DESCRIPTION

FIG. 1 is a top, front and right side perspective view of a mirror defogger, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The electrical cord has been broken away in the middle in FIGS. 2-7 for convenience of illustration.

FIG. 1.

FIG. 4.

FIG. 2.

FIG. 5.

FIG. 3.

FIG. 7.
